Mark A. Ahlmann
ATTORNEYS.

UNITED STATES PATENT OFFICE.

TUDOR F. BROWN, OF NEWARK, OHIO.

POUCH-TRANSFERRING DEVICE.

Application filed October 18, 1925. Serial No. 62,815.

To all whom it may concern:

Be it known that I, TUDOR F. BROWN, a citizen of the United States of America, and resident of Newark, in the county of Licking and State of Ohio, have invented certain new and useful Improvements in Pouch-Transferring Devices, of which the following is a specification.

This invention relates to mail or package transferring devices usually referred to in the art as mail cranes, although applicant's invention is capable of use in connection with the deposit and removal of pouches, bags or the like. In the further description of the apparatus, it will be referred to as in use in connection with mail pouches or bags, but it is to be understood that the terms shall be regarded as including other objects or containers that may be released or gathered during the travel of an aeroplane with respect to stations having the equipment.

It is an object of this invention to provide novel means for suspending a pouch from an air transport of any appropriate type, such as an aeroplane or dirigible, the said suspending means being equipped with a trip or release whereby the pouch is disengaged from its suspending means or carrier in order that pouches which are carried by the suspending means may be deposited at certain stations with respect to which the transport is traveling, and it is a further object of this invention to provide novel means whereby the said suspending device may be operative to collect pouches from stations equipped with a crane of the character indicated.

It is a further object of this invention to provide a crane having means for guiding a suspending device or collector in order that it will be directed into operative relation to the pouch carrier or yoke which the said suspending device will engage in removing the pouches from the crane in order that they may be transferred to the transport.

It is a further object of this invention to so mount the crane as to permit it to turn in different directions in order that it may be relieved of undue strain when the pouch carrier or yoke is dislodged from the crane.

It is furthermore an object of this invention to produce an apparatus of the character indicated which will be strong and durable, as well as efficient and satisfactory in use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in perspective of a crane embodying the invention;

Figure 2 illustrates a sectional view of a suspending head or bell with supports and operating means in elevation; and

Figure 3 illustrates a diagrammatic view of the crane with dotted line showings of attainable adjustments.

In these drawings 10 denotes a suitable base in which a standard or post 11 is rotatable. The post constitutes a support for the crane carrier which in the present embodiment of the invention comprises a horizontal bottom frame member 12, upstanding side frame members 13 and converging horizontally disposed arms 14 and 15 having their ends in spaced relation to each other.

In order that a carrier or suspending device, which will be presently described in detail, may be properly guided for the purpose of depositing its load at a station and further guided to engagement with the pouch carriers which it is to remove from the crane, two substantially horizontal rails or rods 16 and 17 are attached to and carried by the arms 14 and 15 respectively. Preferably, the rails are oppositely curved at their rear ends for the purpose of producing a clearance between their ends so that the distributor or collector which depends from the transport will enter the crane without making it necessary for the distributor or collector to register too accurately with the axis of the crane. In other words, the flared rear end of the crane would allow considerable latitude of movement for the distributor or collector in entering the space between the rails and the rails will act as guides to direct the distributor or collector to the interior zone of the crane. The forward ends of the rails beyond the arms 14 and 15 are preferably flared slightly as shown at 18 and then converge at their ends, but their ends are in spaced relation to each other so that a clearance is produced through which

the suspending means may escape from the crane. The rear ends of the rails may be provided with a suitable support 19, but as the details of construction of the support are immaterial, they will not be described. The illustration is sufficient for an understanding of one embodiment of a support by those skilled in the art.

In order that pouches may be supported

- 10 on the crane for removal by the collecting device of a transport, a yoke 20 may be provided comprising, in the present embodiment of the invention, a length of wire shaped to form a loop 21 so restricted in size as to cooperate with the collector and the said yoke has laterally extending hooks 22 and 23 from which pouches such as 24 may be suspended when the crane is set to permit collecting of the pouches.
- 15 20 As shown in the drawings, the yoke engages and is supported by the crane and the loop 21 is located slightly in advance of the space between the front ends of the bars 16 and 17 so that as the collector passes the 25 ends of the bar, it engages the loop to later remove the yoke from the crane.

- In the present embodiment of the invention, the pouch suspending and delivering device and the pouch collector comprises a head or bell 25 that is supported by suitable cable or rope 26 depending from the transport and the said bell should be of such size as to prevent the loop 21 from disengaging it while the pouches are being collected. The head has an internal flange or web 27 having a pivot 28 therein on which a hook 29 is pivoted, the hook being intended to support pouches to be dropped or delivered as illustrated in Figure 1.
- 30 40 Preferably, the pouches will be provided with loops such as 30 or other hook engaging elements so that the pouches will be suspended from the head until the hook is manipulated to release the load. As here 45 shown the hook is held in operative relation to support the load by a latch 30 movable on a pivot 31 within the head. The latch is held approximately parallel with the lower edge of the head by a flange or wall 32 and the latch is of such length as

to project under the hook. The latch preferably has a camming surface 33 that will permit it to raise the hook when the end of the latch remote from the pivot is moved upwardly in the head and the said movement will raise the free end of the hook until the latch passes the end of the hook after which the said hook will be released and it will swing downwardly and permit the dislodgment of the pouch from the hook. A 60 rope or cable 34 is connected to the latch and it extends through an aperture 35 in the bell and must of course reach to an operator on the transport, which operator upon pulling the cable 34 when the parts are 65 in the position shown in Figure 2 will cause the release of the hook in the manner just described.

The head and bell therefore contains mechanism for supporting and releasing a 70 pouch and coacts with the yoke for dislodging and suspending pouches that are to be collected.

I claim—

1. In a pouch transfer, a head having a 75 suspending means extending therefrom near its transverse center only, a pouch supporting and releasing means therein, and means extending to the releasing means whereby it is manually operated, the said releasing 80 means projecting from the head at a location near its transverse center, the outer surface of the head around the releasing means and the head supporting means being unobstructed and capable of receiving and 85 supporting a pouch engaging element.

2. In a pouch transfer, a head, a suitable supporting cable therefor, a pouch support pivoted in the head, a latch engaging a portion of the pouch support remote from its 90 pivot for holding it in operative position, a flange integral with the head for holding the latch in the said position, and a latch moving means operative to disengage the latch from the pouch support, the said latch moving means projecting through the head in proximity to the location of the supporting cable thereof.

TUDOR F. BROWN.
